UNITED STATES PATENT OFFICE.

JOHN ERNEST LEWIS, OF PASADENA, CALIFORNIA.

STEAM-BOILER.

1,296,978.

Specification of Letters Patent. Patented Mar. 11, 1919.

Application filed April 24, 1917. Serial No. 164,096.

To all whom it may concern:

Be it known that I, JOHN ERNEST LEWIS, a citizen of the United States of America, residing at Pasadena, Los Angeles county, 5 Cal., have invented new and useful Steam-Boilers, of which the following is a specification.

This invention relates to vapor generators.

This invention has utility in connection 10 with portable steam plants, especially for quick response in intermittent use.

Referring to the drawings:

Figure 1 is a perspective view, with parts broken away, of an embodiment of the invention in a motor vehicle propulsion steam plant;

Fig. 2 is a longitudinal vertical section through the boiler or generator of Fig. 1;

Fig. 3 is an end elevation, from the right 20 of Fig. 2, with parts broken away;

Fig. 4 is a fragmentary view, on an enlarged scale of the liquid level maintenance device for the generator;

Fig. 5 is a fragmentary perspective view 25 looking down on the spark control for igniting the furnace or burner;

Fig. 6 is a fragmentary plan view of the steam portion of the generator, parts being broken away;

Fig. 7 is a section on the line VII—VII 30 Fig. 6;

Fig. 8 is a section on the line VIII—VIII Fig. 7;

Fig. 9 is a section on an enlarged scale on 35 the line IX—IX Fig. 7; and

Fig. 10 is a section on an enlarged scale of the manifolds adjacent the header.

The motor vehicle 1 has disposed under the hood 2 the generator having the refractory heat insulation housing having the base 40 section 3, the forward upper housing section 4, the reverse bridge-wall 5 and the rear housing section 6.

The water or liquid supply may be cared 45 for by the steam pump 7 connected by the line 8 through the heat resisting housing with the reserve liquid chamber 9 having a plurality of liquid flow tubes 10 leading downward therefrom, and then forwardly 50 as the manifold sections 11, in parallel series resting on the housing seats 12, 13. To provide increased heat exchange surface, it is preferred to have rise from the manifolds 11, smaller cross section riser tubes 14 terminating in the parallel upper horizontal manifolds 15 extending forwardly into the

transverse header 16. The main steam line 17 may extend therefrom out through the heat resisting duct 18 of the generator housing having the branch 19 for controllably 60 actuating the pump 7. This duct 18 as a jacket for the steam main 17 may extend to the vehicle propelling motor 20 mounted adjacent the rear axle of the automobile 1. Exhaust from this motor 20 may be conducted 65 by the line 21. The radiator 22 may serve as a condenser for exhaust. From the condensed liquid containing supply tanks 23, the feed water may pass by the line 24 to the pump 7.

The feed water line 8 to the boiler from the pump 7 has therein the check valve 25 opening toward the boiler or generator, precluding pressure from the boiler creating any back flow toward the pump 7. This 75 line 8 also has therein the needle valve 26 carried by the sliding yoke 27 actuatable by the heat expanded tube 28 connected by the duct 29 to the chamber 9 at the region of mean water level of said chamber. Accordingly when the liquid level in the chamber 9 exposes this duct 29 to the steam or hot vapor, such higher temperature substance entering the tube 28 and retaining such temperature to a much greater degree than the 80 liquid, especially due to latent heat therein, expands the tube 28, causing the needle valve 26 to seat and close the by-pass line 30, normally returning the water from the pump 7 to the reserve or supply tank 23. With this 85 by-pass closed, the continuously acting pump 7 forces liquid into the line 8, past the check valve 25 into the reserve chamber 9 to raise the liquid level therein. This feeding of liquid to the boiler continues until the 90 liquid level is raised in the chamber 9 to fill the duct 29 and tube 28. Contraction of the tube 28 then opens the by-pass line 30, in order that the continued action of the pump 95 may not still supply the boiler.

Disposed in the chamber 9 is the float 31 carried by the arm 32 on rock shaft 33 having on its portion protruding from the housing the arm 34 movable across the scale 35, which may be disposed for convenient inspection by the vehicle driver in observing whether water level is maintained in the boiler reserve chamber, as a safeguard against burning out of this low liquid volume, quick response, flash approximating 100 boiler.

Spaced from the vapor conducting tubes

of the generator by the lugs 36 to preclude excessive local heating to deterioration action in the generator is the heat conducting hood 37 disposed over the manifolds 15 and 5 header 17 as a shield for the generator against the direct action of the burner or furnace discharge heat source 38. This burner 38 is disposed for providing the initial heat intensification region adjacent 10 the water level region about the great relative heat conducting area of the tubes 14. The upper portions of these tubes 14, above the water line, and the manifolds 15 with the communicating header 16 serve as a va- 15 porizing or steam dome for superheating or drying the vapor, due to the heat conducting action of the hood 37. This localizing of the intense heat for practically surface escape to vaporization is a direct flashing of the 20 liquid to steam without introducing any dampening or retarding by convection due to gas bubble travel through any overlying liquid region. This means practically instantaneous steaming response.

25 The housing about the boiler provides a passage for the boiler enveloping heat flow downward from the burner 38 in a direction opposing the liquid flow. This heat flow passes under the bridgewall 5, about the down 30 flow tubes 10, and rises to pass the reserve chamber 9, that there may be preheating. As a heat retaining jacket, the burner fumes envelop the main 17 in its extent to the motor 20, and for heat economy are used to 35 jacket the cylinders of the motor 20.

Further use is made of this furnace exhaust by having the fan 39 air blast duct 40 in such duct 18. Adjacent the venturi restriction 41 in the duct 40 is the fuel supply 40 duct 42 which may have a float chamber liquid maintained level in the vessel 43. The flattened discharge of the burner 38 is proportioned to the lateral extent of the parallel manifolds 15.

45 Throttle lever 44 adjacent the steering wheel 45 may control the supply of steam to the motor 20 by the line 17. When the power consumption falls below the capacity of the generator or boiler, there may be automatic control for limiting the boiler generation rate, as by rise in pressure acting upon the diaphragm control device 46 for opening the switch 47 and stopping the blast fan driving motor 48, as actuated from the generator or storage battery for vehicle night lighting.

Connected to be actuated from an arm adjacent the throttle lever 44 is the switch 49 for the spark plug 50 disposed in a central 60 region for insuring fuel ignition in the vapor ejection region.

Disposed forwardly in this furnace or burner heat region is the expansion bar or tube 51 having the fixed mounting 52 and the 65 movable end 53 operating in bar expansion

due to heating in the furnace to rock the angle lever 54 and thus automatically open the switch 55 cutting out current consumption at the spark plug 50 after ignition and during any continued period of burning. 70 With the cooling due to discontinuance of the burning, this switch 55 is automatically closed so that the circuit is in condition for reestablishing ignition.

By disposing the reserve chamber 9 adjacent the water level region, there is proportionally therein at such region a large volume of water, giving a stability for narrow range of water level fluctuation in the tubes 14. Further the general disposal of 80 the feed water may intermittently readily respond with a considerable safety leeway. All the flow is against the heat travel. The duct 56 between a central manifold 15 and the chamber 9 is merely for pressure equalization and supplying vapor for the automatic by-pass. There is accordingly provision precluding any circuit for liquid flow in the generator. All liquid flow is progressive 85 and in a direction opposite to the enveloping 90 heat flow.

What is claimed and it is desired to secure by Letters Patent is:

1. A vapor generator embodying a housing providing a first chamber and a second chamber, a boiler having a preheater in the first chamber and a vaporizer in the second chamber, and a heated gas supply adjacent the top of the second chamber for acting upon the upper portion of the vaporizer, 95 said first chamber having a heated gas outlet adjacent its top, and adjacent its bottom communication with the bottom of the second chamber, said preheater including a reserve reservoir in the first chamber disposed at a height near the top of the second chamber, ducts leading downwardly from the reservoir and into said second chamber, said vaporizer having top manifolds and riser ducts extending from the preheater 100 to said top manifolds. 105

2. A vapor generator embodying a housing providing a chamber, a boiler located therein having pairs of upper and lower manifolds, a series of riser ducts between 115 each pair of manifolds, means providing heated gas supply adjacent the upper manifolds, and a shield mounted on the upper manifolds and extending downwardly thereover to protect said upper manifolds from 120 the direct action of the gas supply means, said housing having an outlet near the bottom thereof to take off the heated gas supplied at the top. 125

3. A vapor generator embodying a housing providing a chamber, a boiler located in said chamber, said boiler including a plurality of parallel series of riser ducts, and manifolds to which said ducts deliver, means providing a heated gas supply to the upper 130

portion of said housing adjacent the manifolds, and a downwardly open shield over the upper manifolds for tempering the action of the heated gas.

5 4. A vapor generator embodying a housing providing first and second chambers, said chambers having in the lower portion thereof a heated gas communication passage, said second chamber having therein a plurality of lower manifolds, riser ducts from said manifolds, and upper manifolds to which the risers extend, and a preheating reservoir in said first chamber having a plurality of ducts extending to the lower manifolds, said reservoir being further provided with a duct communicating with an upper manifold, and a burner providing heated gas supply in the upper portion of the second chamber to travel downwardly therefrom about the riser ducts in the second chamber through the communication passage and thence to pass upwardly in the first chamber about the reservoir.

10 5. A vapor generator embodying a reserve reservoir, downwardly extending ducts therefrom terminating in parallel lateral offsets providing lower manifolds, riser ducts in parallel series from said manifolds, upper manifolds to which the riser ducts extend, a header to which the upper manifolds connect, said upper manifolds and header forming a vapor region, a duct providing direct

communication between said vapor region and the reserve reservoir independently of the lower manifolds, and a housing providing a first chamber for the reservoir and downwardly extending ducts, and a second chamber for the upper and lower manifolds, riser ducts and header.

15 6. A vapor generator embodying a housing, a partition in said housing providing a first chamber and a second chamber communicating with each other below said partition, a reserve liquid reservoir in the first chamber, a plurality of ducts extending from said reservoir downwardly in the first chamber over into the second chamber, and riser ducts leading from the extensions of said downwardly extending ducts and in the second chamber, manifolds to which said risers extend, and a header connecting said manifolds in the upper portion of the second chamber, a refractory shield over said manifolds, and a burner for supplying heated gases to the second chamber adjacent said shield, the second chamber providing a passage downward for these heated gases about the riser tubes, thence into the first chamber and upward about the reservoir in a direction counter to the direction of liquid flow 20 from the reservoir.

25 In witness whereof I affix my signature.

JOHN ERNEST LEWIS.
